CLAIM

The ornamental design for a motorcycle tire, as shown and described.

DESCRIPTION

FIG. 1 is a perspective view showing our novel motorcycle tire design;

FIG. 2 is a plan view thereof; and,

FIG. 3 is a side view thereof.

The tread pattern is understood to be repeated uniformly throughout the circumference of the motorcycle tire and the opposite side is the same as the side shown in FIG. 3 of the drawing.

FIG-1

FIG-2

FIG-3
